[57] CLAIM

The ornamental design for a screw-on electrical connector, as shown and described.

DESCRIPTION

FIG. 1 is a front elevational view of a screw-on electrical connector showing our new design, the rear and side elevational views being the same.

FIG. 2 is a top plan view thereof; and

FIG. 3 is a perspective view thereof with the top of the connector in the foreground.

The bottom of the claimed design is unornamented, bearing only features having an appearance dictated by function only.
